KNITTING MACHINE NEEDLE

Joseph P. Primm, Rome, Ga., assignor of one-half to Rome Hosiery Mills, Rome, Ga., a corporation of Georgia

Application June 4, 1941, Serial No. 396,617

4 Claims. (CL 66—121)

This invention relates to improvements in needles such as are used in knitting machines. In making this statement it is desired to add that there is no limitation upon the specific uses of the needle in the broad classification of knitting machines. The particular adaptation contemplated herein for the improved needle is to circular knitting machines, including circular knitting machines which have dial needles combined therewith, but in extension of the idea expressed above the improvement is intended for embodiment in needles employed in any type of knitting machine other than the two expressed, because the particular advantages derived from the improvement will be operative as effectively in the manufacture of one class of knitted goods as in any other.

It is to be observed herein that the improvement is illustrated in a needle of the familiar pivoted-latch type. However, the major structural principles and the advantages derived therefrom are capable of embodiment in spring beard needles although an illustration of the latter is not included herein. The current use of latch needles, the description being confined to that type, has manifested a number of disadvantages which when summarized can be attributed chiefly to undue friction in the process of manipulating the needles with respect to the yarn. This statement is elaborated upon later on, but it leads to an expression of the objects of the invention which are as follows:

First, to provide a latch needle wherein the structure of the hook and latch is so reorganized as to materially reduce the factor of friction in the acts of shedding the stitch and clearing the latch.

Second, to provide a needle of the character described wherein the common faults of currently used latch needles are avoided by the sequestration of the tip of the latch in a recess in the extremity of the hook, said recess occupying a position on the outer perimeter of the hook to provide for a free seating of said tip in the recess during the shedding of the stitch, and as free a departure therefrom when gravitating to its open position.

Third, to provide a needle of the character described, especially of the diminutive sizes used in fine knitting, wherein the width of the modified hook tip is kept within the confines of the thickness of the shank, as distinguished from needles of the type under consideration wherein the spoon terminal of the latch is broader than the shank is thick and for that reason being re-

sponsible for most of the faults which are overcome by the improvement.

Fourth, to materially reduce the difficulties in manufacturing latch needles and consequently to reduce the cost of said manufacture, by virtually eliminating the special shaping of the latch, which as is commonly known is of such an extremely small size that the needed special shaping in the making of the spoon involves an intricate mechanical procedure, and transferring the required finer operation to the hook on which said operation can be performed to better advantage because of its comparatively large size.

Other objects and advantages will appear in the following specification, reference being had to the accompanying drawing, in which:

Figure 1 is a side elevation of the upper portion of a latch needle made in accordance with the invention.

Figure 2 is a front elevation of the hook and latch end of the needle on a much enlarged scale.

Figure 3 is a cross section taken on the line 3—3 of Figure 2.

Figure 4 is a front elevation of the improved needle, illustrating a modified construction.

The needle generally designated 1 is basically the same as currently used latch needles. It comprises a shank 2 which toward its upper end is provided with the cheeks 3 between which the latch 4 is pivoted. Said cheeks merge into the throat 5 which terminates in the hook 6.

The cheeks 3 result from the kerfing of the shank 2 at 7, the kerf providing a chamber in which the heel 8 of the latch is freely swung on its pivot 9. The latch periodically gravitates to the open position (dotted lines, Fig. 1) in the knitting operation, requiring the freedom of motion which is supplied by its free mounting in the kerf 7 as stated.

Attention is first directed to the latch 4 which, as seen in Fig. 2, has a body 10 which for most of its length is made quite thin. It flares laterally at 11 toward the previously mentioned tip, now designated 12. The appearance of the latch when viewed from the front (Fig. 2) is somewhat on the order of a club, the virtue of the flares at 11 and of the ultimate lateral enlargement in the tip 12 being not only the strengthening of this essential part of the latch but more

largely its matching in configuration with the extremity 13 of the hook 6 in the manner presently made clear.

Upon viewing the latch 4 from the side (Fig. 1) it is seen that the breadth of the body 10 remains at approximately a uniform dimension, a

diminution in size being apparent at the approximate point 14 which responds substantially to the beginning of the lateral flares 11 (Fig. 2). A comparison of the latch in Figs. 1 and 2 shows that it is devoid of such special shaping as will classify it with an intricate manufacture. As brought out before and as is commonly known, the latch of a needle especially of the small size used in knitting hosiery comprises an extremely small part.

It is necessarily made so because of its requirement to pass through the loop in the knitting operation, and if it were possible to confine the latch to a substantially straight piece of metal many of the faults encountered in knitting would not arise. However, currently used latch needles are distinguished by a spoon terminal on each latch which is broader than the needle shank is thick in the circumferential direction of the needle cylinder.

Moreover, the current seating of the spoon terminal of the latch upon the outer perimeter of the extremity of the hook accentuates the foregoing excess breadth of the spoon so that in the process of knitting abnormal tension is produced because of the necessity of the loop having to accommodate a greater bulk than would be presented in the absence of the spoon. This circumstance is responsible for correlated factors, namely, the excessive expanse of metal which has to pass through the loop and the resulting increase in tightness of the loop.

Reverting to the latch 4 in Figs. 1 and 2 it is apparent there that the lateral flaring at 11 is the chiefly distinguishing characteristic, the feature of predominating importance resting upon this configuration of the latch, particularly its extreme thinness of the body 10, being that the cheeks 3 can be made thicker than is normally possible. The thickness of the shank 2 in the circumferential direction is the same in the instant needle as it is in current needles. But because of being able to use thinner stock for the body 10 than is currently used for the bodies of latches, the kerf 7 can be made of less width with the result that the cheeks 3 will be thicker.

Attention is next directed to the hook 6, especially the extremity 13. The configuration of the latter is well shown in Figs. 2 and 3 from which it will be observed that the diameter of the hook is expanded into the region of the extremity 13 until the maximum is reached at 15. This maximum falls within the confines of the thickness of the shank 2 as is seen by the projection lines 16, remembering that the basis of the thickness of the shank was previously laid in terms of the circumferential direction of the needle cylinder. The distinction here is that in currently used needles the apparent thickness of the shanks is excessive because of the projection of the lateral margins of each spoon beyond the sides of the respective latch. It is this projection which is responsible for abnormal friction against the yarn especially in the loop shedding operation.

A recess 17 is impressed into the front of the extremity 13. The term impressed is not intended to be a limitation because it is readily conceivable that the formation of the extremity 13 may be achieved otherwise than by a die. For example a plain hook shape may be made and the recess 17 then formed in the outer perimeter of the extremity 13 by means other than through impression. But to carry out one mode of making the hook 6, the acts of producing the

expanded extremity 13 and the recess 17 are responsible to the single stroke of a die.

As is plainly seen in Fig. 3, the recess 17 constitutes an indentation in the front perimeter of the extremity 13. Said indentation is generally of a V shape, although it is desirably modified therefrom by rounding the bottom at 18 as well as the terminals 19 where mergence occurs with the external surface of the extremity. The recess 17 tapers off toward the crown of the hook 6 (Fig. 2) but the major part of it in the region of the maximum 15 is well adapted to the sequestration of the tip 12 of the latch 4.

It is not intended that all of the tip 12 shall be pocketed in the recess 17. The approximate relationship of the latch to the hook is shown in Fig. 3 from which it will be observed that the outer surface 20 of the tip 12 falls substantially within the continuation at 21 of the oval cross section of the hook extremity 13.

The virtue of this relative disposition of the two parts is that a uniform cross-section is preserved at the very place which in current needles is the cause of rupturing the yarn at times because of the projection of the latch spoon beyond the bounds of the hook cross-section. The foregoing uniformity of the hook and latch at the cross sectional point of contact (Fig. 3) makes for perfect smoothness of the contacting surfaces. This smoothness also extends to the extremely near approach to actual blending of surfaces which occurs at the place where the rounding at 22 of the extremity 13 meets the lateral flares 11 of the latch 4.

It will be apparent from Figs. 1 and 2 taken in conjunction with the foregoing statements, that the act of shedding a stitch can be accomplished with the minimum of friction insofar as the needle is concerned. Said act occurs when the latch is closed as shown, and by virtue of eliminating outstanding obstructions such as the sides of a spoon on the latch of a currently used needle it follows, as has been stated, that excessive friction and the tendency to rupture the yarn are virtually non-existent.

A similar advantage occurs in the act of clearing the latch, in other words, when the needle is projected upwards preparatory to drawing down a new stitch. At that time the latch 4 recedes in the kerf 7, occupying the dotted line position (Fig. 1) against the shank of the needle. From an examination of Fig. 2 it is readily visualized that the tip 12 comes well within the theoretical boundary of the shank 2, it being plain that this is so because of the noticeably narrower cross dimension of the tip 12 as compared with the thickness of the shank.

Thus in clearing the latch there is again the absence of setting up excessive friction against the yarn, providing the occasion to point out that under the same circumstance in a current type of needle the frictional effort required in shedding the stitch when the needle is closed being repeated when clearing the latch in the open position of the latter, the outstanding sides of the spoon each time being responsible for the inordinate friction. The tendency to cut the yarn in the act of clearing the latch is magnified in current needles because of the then exposed edges of the spoon being considerably sharper than the rounded edges of the spoon which are presented to the yarn in the stitch shedding position.

Toward the end of diminishing the thickness of the latch and complementarily reducing the

lateral dimension of the extremity of the hook even more than disclosed in Figs. 1, 2 and 3, the modification in Fig. 4 is included in this disclosure to show how the latch may exist substantially as a straight piece of metal as suggested above. All parts in Fig. 4 are identified by the reference numerals of corresponding parts in Fig. 1, being distinguished therefrom by the exponent letter *a*. The latch 4a may be of uniform thickness from its pivot 9a to the tip 12a, but desirably is slightly tapered at 23 from approximately a point midway of the body 10a to the tip 12a. By an extension of the idea of tapering it is not imperative that this shall start midway of the distance between the extremities of the latch because it is conceivable that the taper might begin at the pivot 9 and be continuous to the tip 12a.

The advantage of the diminished size of latch insofar as thickness is concerned, resides in the 20 capability of reducing the lateral expanse of the hook extremity 13a. The recess 11a is required to be only broad enough to allow the seating of the tip 12a, this being interpreted to mean that the extremity 13a is correspondingly narrow.

In fact said extremity 13a can be appreciably diminished in size from the cross section of the hook 6a and yet provide an ample area of metal for the formation of the recess 11a as well as an adequate resting place for the tip of the latch when in its closed position. It is desirable that the outer and inner edges of the latch 4a shall be rounded, thereby to diminish still further the frictional component against the yarn as well as to avoid the chance of cutting the yarn.

It is now desired to elaborate upon the common faults occurring in the process of knitting and the manner in which the improved needle overcomes them. As previously stated, the chief advantage of the improvement is attributed to the reorganization of the chief components of the needle whereby undue friction is eliminated as between the needle and the yarn in the act of knitting. The side portions of the spoon on the latch in current needles cause a supertension on the yarn both in shedding the stitch and in clearing the latch. The result is excessive friction and a rapid wear on the needle parts.

By condensing the latch, so to speak, in other words by restricting its free tip to a lateral dimension well within the confines of the needle shank thickness, and at the same time keeping the hook extremity 13 also within said confines despite the fact of its expansion it has become possible to definitely eliminate undue friction both in the acts of shedding the stitch and clearing the latch. One of the results is that the wear on the needle is materially reduced, so that replacements are not required as often as at present.

It is commonly experienced in practice that breakages both of the yarn and needles will occur at the most inopportune times. These breakages are directly attributable to the previously mentioned supertension on the yarn because of having to move excessive thicknesses of metal past the yarn in the stitch shedding and latch clearing operations. Whenever a needle breaks a fault will occur in the character of the knitting, producing what is known as seconds. This same fault will show in the knit fabric when the thread breaks. It can readily be seen that by eliminating to a very large extent the source of both faults, as has been done by the improved needle, there will be fewer broken needles, fewer

occurrences of broken thread and finally fewer seconds.

A factor of considerable importance is that the instant needle produces a very satisfactory, uniform stitch. This is due to the fact that the yarn is never stretched to excess. The direct result of said uniform stitch is a noticeably finer and smoother fabric. This is satisfactory both from the standpoint of the manufacturer and to a less degree from the standpoint of the ultimate wearer. The latter is critical of the fabric from the standpoint of its appearance, but this traces back to the manufacture of said fabric because when the latter is smooth as stated, being devoid of places under undue tension, it becomes possible to dye the fabric with a far greater degree of uniformity than is now possible.

Reverting to the step of clearing the latch, it is known that a definite downward drag occurs on the latch while the needle is on its way to position the yarn below the latch. Similarly, a definite upward drag occurs on the latch while the needle is on its way down to a position whereat the stitch is shed. On both occasions the drag on the latch has a tendency to elongate the pivot hole. Not only is there this tendency, but actually the pivot hole is elongated, resulting in such a loosening of the latch that upon closure of the latch the spoon will fail to register with the extremity of the hook, causing the tip of the latch to extend an objectionable distance upwards of the hook, making the latch project forwardly of the hook even more than in a new needle. The effect is an even greater friction against the yarn, and this is repeated in the instance where the latch fails entirely to lie against the hook, being displaced to one side or the other as the direct result of the loosening of its pivot. As readily seen that when this happens there will be a jamming of the latch against the side of the hook, preventing the latter from gravitating when it should and exposing the hook to a catching of the stitch when the stitch should be shed.

An outstanding fault of the spoon on the latch is its being vulnerable to a constant wearing down on the outside until the inside lateral edges become sharpened to an amazing degree. Consequently when the needle rises to clear the latch, in other words when the needle is moved up past the yarn to bring the latter to a position below the latch, said sharpened edges traverse the yarn and frequently cut it. By keeping the tip of the latch within the confines of the thickness of the shank there is practically no such wear on the latch as will cause the sharpening of the inner edges. Consequently the likelihood to cut the yarn is greatly diminished.

The instant needle is capable of knitting a greater number of plies of yarn than is possible with commonly known needles. This is because of the fact that less friction is involved in the operation of the improved needle.

In plaiting wherein a fine grade of yarn is backed by a cheaper grade or wherein a face yarn of one color is backed by a yarn of another color, it is essential to maintain the two yarns in the same relationship to the machine between the yarn guides and the needles. The necessity for this requirement arises from the fact that if said yarns should reverse themselves in position there would also be a reversal of the relationship of the yarns to the knitted goods. The excess tension produced by currently used needles is often responsible for a reversal in position of the

facing and backing yarns. As already emphasized above, the instant needle totally eliminates all excess tension, thereby recommending it especially for use in plaiting.

Additionally to the above it is a common requirement that there shall be a decided difference in the tension of the two yarns in a plaiting operation. The excess tension occurs on the backing yarn and is much more than is used in common knitting. This excess tension is necessary to keep the backing yarn above the facing yarn while on the needle. Because of the material lessening of disturbing influences by reason of eliminating abrupt projections from the contour of the latch it has become possible to feed the backing yarn under less tension because it will remain properly disposed without the necessity of the excess tension.

The nearly universal practice of using a heavier yarn for the facing in making plaited fabrics thereby to cover up imperfections appearing on the face of the fabric because of a reversal of the threads, is capable of being departed from by use of the instant needle in conjunction with facing and backing yarns of the same size. The reason for this is that there are so fewer instances of misplaiting that there is no necessity of using a facing yarn of heavier gage because of there being little or nothing to have to cover up.

In conclusion it is desired to state that the foregoing listing of advantages derived from the use of the improved needle in contradistinction to the faults of the commonly known existing needle does not complete the statements that could be made in the foregoing behalf. Actually a number of other advantages are derived from the improved needle, and important ones at that, but it is preferred to rest the description here so that full emphasis may be gained by a considerable of what has been set forth.

I claim:

1. A knitting needle comprising a shank having a throat terminating in a hook with which to loop a yarn strand into a stitch, said hook having an extremity of a lateral dimension differing from the diametrical size of the throat and hook

and being provided with an elongated recess on its outer perimeter, said recess extending from a point adjacent the top of the hook to the free end, and a latch pivoted at one end to the shank, having a free end which is of less thickness than the throat and being adapted to seat in the recess and be confined therein so that the combined outer faces of the hook and free end of the latch will present a smooth surface to the thread.

2. A knitting needle comprising a shank having a throat of less diametrical size than the thickness of the shank in the circumferential direction of a cylinder in which said needle is useable, a hook branching from the throat for looping a yarn strand into a stitch, said hook having an extremity expanded laterally so as to be broader than the throat is thick, the maximum dimension of said extremity lying within said thickness of the shank, a recess in the outer perimeter of the extremity, and a latch pivoted at one end on the shank and having an enlarged tip adapted to rest in said recess within the confines of said expanded terminal.

3. A knitting needle comprising a shank having a throat merging into a hook, said throat and hook being of less diametrical size than the shank is thick in the circumferential direction of a cylinder in which said needle is useable, said hook having an extremity diminishing to a size less than the diameter of the hook and throat and having an external recess, and a latch pivoted at one end to the shank and having a tapering free end adapted to seat in the recess.

4. A knitting needle comprising a shank having a hook to loop a yarn strand into a stitch, said hook having an extremity with an external recess elongated in the direction of the hook, said recess having a rounded bottom and rounded side terminals merging into the cross section of the extremity, and a latch pivoted at one end to the shank, having a tip at its free extremity of cross-sectionally substantially ovoid shape to occupy the recesses in shedding the stitch and falling substantially within the circumferential contour of said extremity.

JOSEPH P. PRIMM.
